BOILER FURNACE

Ervin G. Bailey, Easton, Pa., assignor to Fuller
Lehigh Company, New York, N. Y., a corpora-
tion of Delaware

Application January 27, 1927, Serial No. 163,867
Renewed November 14, 1931

4 Claims. (Cl. 122—235)

This invention relates to a boiler furnace, one or more walls of which are kept cool by water tubes connected to the circulation system of the boiler, and through which there is also a local circulation of water. The invention will be understood from the description in connection with the accompanying drawings, in which Fig. 1 is a side view partly in section showing an illustrative embodiment of the invention, and Fig. 2 10 is a front view of the same.

The invention will be described in connection with a Stirling boiler, but it is to be understood that it is applicable to boilers of other types. In the drawings, reference characters 5, 6 and 7 15 indicate the three upper drums of a Stirling boiler, of which the lower or mud drum is shown at 8. These drums are connected by banks of tubes 9, 10 and 11 and tubes 12 and 13 connect the upper drums. The boiler is provided with 20 the usual baffles and outlet for waste products of combustion and also with a superheater.

A furnace 15 is located below the boiler and is illustrated as being provided with a chain grate stoker 16, although it is to be understood that the 25 furnace may be provided with oil, gas or fuel burners if desired. A row of tubes 17 extends along the front wall of the furnace, and is lined on the inside with refractory material 18 that may be made, for example, in the form of blocks 30 having a metal back to contact with the tubes and faces of refractory material toward the inside of the furnace. The upper ends of the tubes 17 are connected to a header 19 and the lower ends to a header 20. A tube 21 outside of the 35 boiler setting connects the drum 8 to the header 20 and a tube 22, preferably less in cross sectional area than the row of furnace wall tubes, outside of the boiler connects the headers 19 and 20, while the tube 23 connects the header 19 to the 40 upper drum 7. A valved drain pipe 24 may be provided for the header 20.

The operation is as follows: Feed water is introduced into the boiler at any convenient point, and hot products of combustion from the furnace passing across the banks of tubes 9, 10 and 45 11 generate steam. Water passes from the drum 8 through the tube 21 into the header 20, and thence into the tubes 17 where it receives heat from the furnace 15 and the mixture of steam 50 and water rises into the header 19, where they are partially separated, the steam for the most part passing through the tube 23 into the drum 7 and most of the water passing downwardly through the tube 22 into the header 20. There 55 is thus a local circulation of water through the

tubes 17 and 22 in addition to the water that passes from the tube 21 into the header 20 and tubes 17.

I have found that in order to obtain satisfactory local circulation in the tubes 17 and 22 it is necessary to have the friction in the tube 23 of considerable magnitude. This may be accomplished by having this tube 23 of small size or by having a valve or restricted orifice therein that will provide the desired friction. 65 By preventing too much water from flowing upwards through tube 23, the static head in the tubes 17, that arises because of the difference in the density of the water in tube 21, etc., and the tubes 17, always exceeds the friction in these 70 tubes 17, so that water will constantly circulate upwardly through tubes 17 and downwardly through tube 22 while the furnace is operating. For example, satisfactory results have been obtained by so restricting the flow through tube 23 75 that about 9 parts of steam to 1 part of water by volume (or 9 parts water to 1 part steam by weight), at pressure of 225 pounds, would flow upwardly through tube 23. Under these conditions the flow of water downward through tube 80 22 is practically all water and represents about 80 times as much by weight as the steam generated. The flow upward through tubes 17 is a mixture of steam and water with about 93 times as much water by weight as there is steam generated. On a volume basis this is equivalent to approximately 48% water and 52% steam at the upper end of tube 17. A steam volume of not over 50% at this point has been found to be a safe figure and the pipes are made of such sizes 85 as to produce this condition. Also, restricting the tube 23 so that approximately equal volumes of water and steam pass through it, has been found to be a condition that will cause satisfactory local circulation to take place. 95

The following are some of the advantages that have been obtained by using this invention:

(a) Due to the fact that the boiler water circulates through the furnace wall tubes, the concentration of impurities in all portions of the 100 water remains approximately the same as that in other portions:

(b) The small amount of water that is returned through the restricted tube 23 does not 105 agitate the water in the drum 7 so much as to produce an appreciable increase in the wetness of the steam that is withdrawn from the boiler:

(c) Sufficient recirculation will take place in the tubes 17 when the boiler is starting up and 110

before it begins to steam, so that the danger of the tubes 17 being burned out is eliminated:

(d) The small size and low cost of tubes 21 and 23 permit great flexibility for expansion between 5 boiler and walls by reason of their small size, and more satisfactory connection to the boiler drums can be secured since the tubes are small enough to be expanded directly into the drums without the use of saddles or nozzles required by 10 larger pipes.

I claim:

1. In combination, a vapor generator comprising a plurality of upper drums and at least one lower drum with tube banks connecting the upper and lower drums and having a maintained liquid level, furnace walls enclosing a combustion chamber arranged to burn solid fuel in a bed for heating said generator, furnace wall protecting tubes having the major lengths above said fuel bed and spaced along the combustion chamber side of at least one of the walls, compartments, one connecting the upper adjacent ends of said tubes and the other the lower adjacent ends, both submerged beneath the liquid level 20 of the boiler drums, a connection from the upper compartment to the generator proportioned to take away only part of the liquid caused to move upwardly of the tubes by heat of combustion, a connection between the compartments returning 25 the remainder of the liquid to the lower compartment, and a supply connection from the lower drum of the boiler to the protecting tubes constantly replacing with liquid any liquid and vapor removed from the upper compartment.
35. 2. In combination, a vapor generator comprising a plurality of upper drums and at least one lower drum with tube banks connecting the upper and lower drums and having a maintained liquid level, furnace walls enclosing a combustion chamber arranged to burn solid fuel in a bed for heating said generator, furnace wall protecting tubes spaced along the combustion chamber side of at least one of the walls and in the combustion chamber area, compartments, one connecting the 40 upper adjacent ends of said tubes and the other the lower adjacent ends, both submerged beneath the liquid level of the boiler drums, a connection from the upper compartment to the generator proportioned to take away only part of the liquid caused to move upwardly of the tubes by heat of combustion, a connection between the compartments returning 45 the remainder of the liquid to the lower compartment, and a supply connection from the lower drum of the boiler to the protecting tubes constantly replacing with liquid any liquid and vapor removed from the upper compartment.

to the lower compartment, and a supply connection from the lower drum of the boiler to the protecting tubes constantly replacing with liquid any liquid and vapor removed from the upper compartment.

80

3. In combination, a vapor generator including a vapor and liquid separator having a maintained liquid level and a lower liquid chamber with a bank of tubes connecting the separator and chamber, furnace walls enclosing a combustion chamber arranged to burn solid fuel in a bed for heating said generator, furnace wall protecting tubes spaced along the combustion chamber side of at least one of said walls and having the major portion of their lengths above the solid fuel bed, compartments, one connecting the upper adjacent ends of said tubes and the other the lower adjacent ends, both submerged beneath the liquid level of the boiler, a connection from the upper compartment to the generator proportioned to take away only part of the liquid caused to move upwardly of the tubes by heat of combustion, a connection between the compartments returning the remainder of the liquid to the lower compartment, and a supply connection from the lower chamber of the boiler to the protecting tubes constantly replacing with liquid any liquid and vapor moved from the upper compartment.

85

4. In combination, a vapor generator including a vapor and liquid separator having a maintained liquid level and a lower liquid chamber with a bank of tubes connecting the separator and chamber, furnace walls enclosing a combustion chamber arranged to burn solid fuel in a moving bed in said furnace for heating said generator, furnace wall protecting tubes spaced along the combustion chamber side of at least one of the walls opposite the advancing solid fuel bed, compartments, one connecting the upper adjacent ends of said tubes and the other the lower adjacent ends, both submerged beneath the liquid level of the boiler, a connection from the upper compartment to the generator proportioned to take away only part of the liquid caused to move upwardly of the tubes by heat of combustion, a connection between the compartments returning the remainder of the liquid to the lower compartment, and a supply connection from the lower chamber of the boiler to the protecting tubes constantly replacing with liquid any liquid and vapor removed from the upper compartment.
